UNITED STATES PATENT OFFICE.

FRANK A. HOWARD, OF CHICAGO, ILLINOIS, ASSIGNOR OF ONE-HALF TO RUSSELL WILES, OF RIVERSIDE, ILLINOIS.

CONDENSER FOR AUTOMOBILE-RADIATORS.

1,234,030.

Specification of Letters Patent. Patented July 17, 1917.

Application filed January 18, 1916. Serial No. 72,720.

To all whom it may concern:

Be it known that I, FRANK A. HOWARD, a citizen of the United States, residing at Chicago, in the county of Cook and State 5 of Illinois, have invented a new and useful Improvement in Condensers for Automobile-Radiators, of which the following is a specification.

My invention relates to improvements in 10 condensers for automobile radiators. The object of the invention is to provide a simple and efficient condensing apparatus capable of being applied to standard automobile radiators without altering their construction 15 or interfering with or changing their normal operation.

The invention will be more fully understood from the following detailed description of some specific embodiments thereof, 20 taken in connection with the accompanying drawings, in which:—

Figure 1 is a longitudinal section through the filler neck of one common type of automobile radiator, showing the manner of applying my condenser thereto.

Fig. 2 is a section on the line 2 of Fig. 1.

Fig. 3 is a broken view similar to Fig. 1, but showing a different manner of applying the condenser and also illustrating a thermometer in place on the condenser.

Fig. 4 is a section illustrating a further modification of the means for attaching the condenser, and

Fig. 5 is a section on the line 5 of Fig. 4.

Referring first to Fig. 1, the numeral 10 designates the upper shell portion of an automobile radiator, which shell commonly carries a vertically extending filler-neck 11. In the construction shown the neck 11 is frustoconical in shape with an upwardly facing shoulder 12 from which rises the internally threaded cap-receiving portion 13. In common practice this neck will be closed by an externally threaded generally cup-shaped cap which engages the threads of the neck and may seat against a packing gasket on the shoulder 12.

For relieving pressure created by generation of vapor or by expansion of the liquid 50 within the radiator and its connected circulating system it is necessary to provide a vent orifice of some description. The almost universal method of venting radiators is to provide a vent or overflow pipe such as 55 the pipe 14 of Fig. 1, this pipe having its

open upper end extending above the normal water level in the neck and usually almost to the top thereof, the other end of the pipe being led outside of the radiator and vented to the atmosphere at any desired location, 60 usually adjacent the bottom of the radiator.

For applying my condenser to such a radiator construction as I have described, I provide first a special form of gasket, designated 15 and preferably comprising a relatively stiff annulus of metal or fiber having a perforation to receive the end of the pipe 14 and carrying a soft resilient facing member which by its resiliency will form a seal around the pipe. This gasket I slip into the 65 filler-neck as shown in Fig. 1, permitting it to seat upon the shoulder 12 therein with the resilient facing on the upper surface.

For coöperating with this special gasket I provide a special form of radiator cap 16, 70 having an internal depending flange 17 of a diameter equal to that of the central hole in the annular gasket 15 and adapted, when the cap is screwed into position, to seat upon the upper face of the gasket and thus cut off 75 the annular chamber 18 into which the upper end of the vent pipe 14 enters from the interior of the radiator.

The condenser proper of my invention is shown in Fig. 1 as a simple conical reflux 80 worm 20 having its inlet end 19 tapped into the center of the cap 16 and having a relief pipe 21 connected with its upper convolution and tapped into the cap to enter the annular chamber 18 and thus form communication 85 with the vent or overflow pipe 14. The lower convolution of the worm may be protected by wings 22 cast integrally with the cap.

The operation of my condenser is as follows:

The vapors evolved within the radiator, or the circulating system of which it is a part, rise to the free surface of the liquid within the shell 10 or filler neck 11 and entering the condenser inlet 19 work their way upwardly through the convolutions of the coil, being gradually cooled by contact with the walls and finally condensed. The condensate drains downwardly to the inlet 19 and drips back into the radiator to replenish 100 the liquid therein. So long as the vapors are evolved at a rate below the condensing capacity of the coil this action will continue, the whole of the distillate being returned 105 continuously through the reflux condenser. 110

If, however, the distillation rate exceeds the rate of condensation, uncondensed vapors will pass the top convolution and enter the relief pipe 21, traversing the latter and entering the annular chamber 18 from which they will be vented by the pipe 14, which thus performs its intended work of preventing excessive pressure within the radiator and furthermore vents the uncondensed vapors passing through the worm at the very place and in the same manner as it would, in the absence of my condenser, vent all of the vapors generated within the radiator. So also, when the radiator is completely filled with cold liquid, and the subsequent heating thereof causes an expansion of the liquid, the excess volume passes freely upward through the worm and by the relief pipe is conducted to chamber 18, thence to the pipe 14 and overflows through the latter in exactly the fashion intended by the designer of the radiator. When it is desired to fill or inspect the interior of the radiator the cap is unscrewed in the customary manner, the gasket being left in place unless a larger opening than that afforded by its central hole is required.

It will, therefore, be seen that my condenser, while serving its intended purpose of condensing and returning to the radiator the liquid distilled therein, does not interfere with or modify the functions and arrangements of the existing structure.

In Fig. 3 I have shown a different form of radiator filler-neck designated 23 and having a plane cylindrical inner bore with external threads 24 for the cap. With this form of neck I prefer to make use of the standard cap 25 which is supplied therewith, fastening the condenser to the cap by drilling holes through the latter. Thus the inlet end member 26 of the worm, which may be a separate elbow casting, is let into a hole in the center of the cap and secured in place by a bell-shaped nut 27 which itself forms the desired internal flange corresponding to the flange 17 of Fig. 1. The lower end of the relief pipe, designated 28, is let into a drilled hole near the periphery of the cap and secured in place by a small nut 29. Since the radiator neck itself provides no shoulder upon which to seat the necessary gasket or horizontal partition, I form the latter as a flanged cup 30, the flange 31 of which seats upon the upper end of the neck while the bottom is perforated to form the large central opening 32 for registry with the bell-nut and the smaller opening to receive the vent pipe 14.

In this form of the invention I have shown the condenser worm as capped by a triangular casting 33 which serves as a connection between the upper convolution 34 thereof and the relief pipe 23. This connection may be enlarged to house the bulb

of a thermometer 35 which extends upwardly through a slot 36 in the casting so that the level of liquid therein may be read by transmitted light.

The thermometer, when so located, will give visible warning of the evolution of vapors at a greater rate than they can be condensed, since under these conditions only will they flow through the connection in which the bulb is located. This location of the thermometer is also an advantageous one for quickly and accurately determining atmospheric temperature for the reason that while the radiator itself forms a considerable reservoir of heat and cools only very slowly after having been heated, the upper portion of the condenser will reach atmospheric temperature within a very short time after the actual evolution of vapors within the radiator ceases.

In Figs. 4 and 5 I have shown a method of applying the condenser to an ordinary form of radiator cap by drilling a single hole in the cap. The construction here illustrated is identical with that of Fig. 3 save for the condenser mounting, which is here shown as a single casting 37 having vertical and horizontal nipples 39, 38 for the attachment of the inlet end and relief pipe of the condenser. The nipple 39 is in communication with a cored passage 40 which leads downwardly through the casting and terminates at the threaded end 41. A securing nut 42 of the form shown is threaded upon this end, the nut being chambered internally to communicate with the crescent-shaped passage 43 which leads from the nipple 38, and having an aperture 44 which opens into the annular vent chamber. The evolved vapors here pass to the condenser, and the condensate returns to the radiator through the passage 40, while the vented vapors or liquid entering the nipple 38 pass downwardly through the passage 43, into the chambered nut and from the latter to the annular chamber and vent pipe 14.

Although I have shown and described in considerable detail some specific embodiments of my invention, it is to be understood that these are by way of illustration only, and that I do not regard my invention as limited thereto except in so far as I have included such limitations within the terms of the following claims, in which it is my intention to claim all novelty inherent in my invention as broadly as is possible in view of the prior art.

What I claim as new and desire to secure by Letters Patent is:—

1. In combination an automobile radiator cap, a reflux condenser carried thereby and having its intake end connected through the cap with the interior of the radiator, and means connecting the distal end of the condenser with the radiator overflow pipe.

2. In combination an automobile radiator cap, means forming with the cap an annular space open to the radiator overflow pipe and a central space open to the radiator, and a reflux condenser carried by the cap and having its intake end connected to the central space and its distal end to the annular space.
- 5 3. In combination an automobile radiator having a filler neck extending upwardly from the water compartment thereof, an overflow pipe extending upwardly from the body of the radiator into the said filler neck, an annular gasket lying within the said neck and having a perforation to receive the said
- 10 overflow pipe, a cap adapted to close the said neck and having a depending flange for seating upon the said gasket to form an annular compartment into which the upper end of the overflow pipe projects, and a reflux condenser carried by the said cap and having its intake end connected through the cap with the interior of the radiator and its distal end connected with the said annular compartment.
